UNITED STATES PATENT OFFICE

2,430,958

SHOE POLISHING APPARATUS

Benjamin Silfen, Chicago, Ill.

Application May 11, 1944, Serial No. 535,012

1 Claim. (Cl. 15—266)

1

This invention relates in general to a shoe polishing apparatus and is more particularly described as a kit and container for shoe cleaning and polishing materials, also providing a raised foot plate upon which the foot rests for facilitating the cleaning and polishing process.

An important object of the invention is to provide a foot rest in conjunction with a container for shoe polishing articles having also parallel bars at the sides of the foot rest which serve both to assist in enclosing the articles and also to aid in their use in the shoe polishing operation.

A further object of the invention is to provide a combined container for a shoe polishing kit which is made entirely of wood or other non-critical material such as plastic or composition which is not subject to requirement for war purposes.

A further object of the invention is to provide a shoe polishing container having a hinged foot plate which is releasably locked in place at the top thereof to retain shoe polishing articles in the container.

Another object of the invention is to provide a combined shoe polishing apparatus and container which is generally of new and improved construction and material characterized by simplicity of design as well as ease and facility of use, assembly and operation.

Other objects of the invention and the various advantages and characteristics of the present combined apparatus and container will be apparent from a consideration of the following detailed description.

The invention consists in the several novel features which are hereinafter described and more particularly defined by the claim at the conclusion hereof.

In the drawings which accompany and form a part of this specification or disclosure and in which like letters and numerals of reference denote corresponding parts throughout the several views:

Figure 1 is a perspective of a shoe polishing apparatus with the top or foot plate in raised position;

Figure 2 is a cross sectional view of the structure shown in Figure 1 with the foot plate in closed position; and

Figure 3 is a sectional detail taken on the line 3—3 of Figure 2.

A shoe polishing apparatus has heretofore been provided with bars or rollers at the side of a fixed or movable foot plate over which polishing strips or cloths are movable for the purpose of cleaning

2

and polishing a shoe, but the present invention incorporates a foot support and cloth engaging bars as a part of a structural container in which the foot plate is utilized as a top and retaining device for a receptacle in which the bars are also mounted, the bars and the top plate providing means for holding other devices and equipment used in polishing compactly within and substantially enclosed thereby.

10 Referring now more particularly to the drawings, a container, open at the top, has ends 8 and 9 secured to lower sides 10 and all supported in upright position at the margin of a base or bottom 11. At each corner of the under side of a base, a supporting button 12 of rubber or other material may be provided.

One of the ends 8 is provided with a recess or slot 13 in its upper edge for receiving a foot plate 14 therein, rotatably mounted upon a pivot 15 inserted from one extremity of the end. In order that the foot plate will fit closely over the container, the bottom 15' of the slot 13 is inclined downwardly at the outside of the slot to enable the plate to assume an inclined position and also to limit the upward inclining movement of the plate.

The other end piece 9 is provided with a similar recess or slot 16 of a width to receive the free end of the plate 14 therein and of a depth to seat the plate substantially flush with the top thereof. In the free end of the plate is a notch 17 to receive the rounded end 18 of a flat spring catch 19 secured to the outer side of the end 9 below the slot and adapted to hold the plate releasably seated in the slot 16.

Extending between the ends 8 and 9 additionally supporting and holding them together, are two side rods 20. These rods are located at some distance above the bottom to provide space below them for inserting articles in the kit, they are spaced inwardly from each of the sides 10 to allow the extremities of cleaning and polishing cloths 21 and 22 to be inserted freely around the rods from the inside and outside thereof; and they are located below and outside of the sides of the foot plate 14 so that a cleaning cloth or strip inserted under both rods may be confined closely against the sides and over the top of a shoe placed upon the plate 14.

In the cleaning operation, the foot plate 14 is preferably closed over the receptacle and it is commonly provided with a ribbed anti-slipping cover 23 of rubber or any similar material extending from end to end, and with a cross piece 24

for engaging the heel of a shoe when placed thereon.

The interior of the container below the plate 14 and the side rods 20 provides sufficient space for the articles of a shoe polishing kit which may consist of a cleaning brush 25, the ends of which are inserted below the bars at one end of the container to hold it in place; polish holding cans 26 and 27, a bottle 28 of shoe cleaning preparation, a dauber 29 for swabbing the shoes with cleaner or polish. In assembling the kit, the loose parts above named are packed within the container, and the cleaning and polishing cloths 21 and 22 are placed over the tops of the articles and the cover plate 14 is closed over and upon the cloths until it is engaged by the catch 19 at the end of the container.

With this construction, all the articles of the shoe polishing and cleaning kit are compactly arranged and held in the container, the foot plate and the side rods constitute the parts of the apparatus about and over which the cloths are moved in cleaning and polishing a shoe positioned on the foot plate; and the cleaning and polishing accessories are freely and readily inserted and removed from the container when the foot plate 14 is raised and inclined upwardly from the container.

It is believed unnecessary to show the application of the cleaning and polishing cloths to a shoe when resting upon the plate 14 as the method of applying the cloths and moving them in contact with the front, sides or heel of the shoe is well known in practice.

The use of this apparatus may render brushes unnecessary except for the removal of mud and dirt. By having the receptacle compact and substantially flat, it may be placed upon a stool, chair, or other support, not too high, and the foot and shoe of a user may be positioned thereon for convenience in use.

The invention is not to be understood as restricted to the details set forth since these may be modified within the scope of the appended claim without departing from the spirit and scope of the invention.

Having thus described the invention, what I claim as new, and desire to secure by Letters Patent is:

As a new article of manufacture, a shoe shining apparatus comprising a flat rectangular base, a pair of parallel laterally spaced side walls connected fixedly to, and extending upwards from,

the side margins of the base and having straight parallel equal height upper edges, a pair of parallel laterally spaced end walls connected fixedly to, and extending upwards from, the end margins 5 of the base, having the end margins thereof in abutment with the end margins of said side walls, having their upper margins projecting above the upper edges of the side walls and provided with aligned, horizontally elongated notches in their 10 central upper portions, and forming with the base and the side walls an open top compartment for storing shoe shining equipment, a pair of parallel horizontally extending rods spaced inwards from, and in parallel relation with, the side walls, 15 having the ends thereof connected to the end walls, and positioned so that their upper portions are substantially flush with said upper edges of the side walls, and a flat rectangular foot plate adapted normally to assume a closed position 20 wherein it extends between the end walls and has its ends disposed in the notches, shaped and arranged so that when it is in its closed position its side edges are spaced inwards and upwards from the rods and it, together with the 25 rods, closes the top of the compartment against displacement of the equipment therefrom, and pivoted so that it may be swung upwards from its closed position into an open position in order to provide access to the equipment in the compartment, the spaces between the rods and the 30 upper edges of the side walls and the spaces between the rods and the side edges of the foot plate when the latter is in its closed position being comparatively narrow but sufficient to permit a fabric shoe shining strip to be threaded so that it overlies the foot plate and underlies 35 and extends upwards from the rods.

BENJAMIN SILFEN.
